CODE COMMUNICATION SYSTEM FOR
RAILROADSWilliam M. Barker, Greece, N. Y., assignor to
General Railway Signal Company, Rochester,
N. Y.

Application July 21, 1944, Serial No. 545,973

7 Claims. (Cl. 177—353)

1

This invention relates to communication systems for railroads, and more particularly to a code communication system of the so-called shunt type for centralized traffic control systems combined on the same pair of line wires with a telephone system using electro-mechanical selectors at way stations to effect selective calling of way stations.

In one type of code communication system for centralized traffic control on railroads, commonly known as the shunt type system and disclosed, for example, in the prior application of Hailes, et al. No. 484,728, filed April 27, 1943, now U. S. Letters Patent 2,399,734 granted May 7, 1946, the code elements for controls and indications are transmitted over a pair of line wires without changing their continuity and in such a way that these same line wires may be employed for telephone communication and the like.

In a code communication system of this character, conveniently termed a C. T. C. system, the field start to initiate operation of the system is accomplished by shunting the line wires at a field station where a change in the occupancy of a track section or the like calls for the transmission of new indications. A field station equipment is operable to shunt the line wires for such a field start only when the associated line relay is energized with a certain polarity.

Assuming such a type of code C. T. C. system, it is often desirable to employ the same line wires for telephone communication and selective ringing by electro-mechanical selectors bridged across the line. One type of selector system, commonly used and known as the Western Electric train dispatching telephone system, uses an electro-mechanical selector of the type which is operated by pulses of alternate polarity, and which is sometimes called an A. C. selector.

When such a selector system is combined with a code C. T. C. system of the shunt type above mentioned, it may happen that some of the selector code pulses will be of sufficient intensity and duration to energize the line relays of the C. T. C. field equipment with the polarity permitting a field start, thereby allowing a C. T. C. field station where some change in track circuit occupancy or the like has occurred, to apply a shunt across the line wires during transmission of the selector code and thereby mutilate that code, or otherwise interfere with the desired operation of the combined system.

In view of these considerations, the primary object of the present invention is to provide an 55

2

improved organization and arrangement of parts and circuits for a centralized traffic control system and a mechanical selector system combined on the same pair of line wires, in such a way that the line relays of the C. T. C. system are not operated by the pulses in the selector code, or at least are not energized sufficiently to permit a field start.

Generally speaking, and without attempting to define the nature and scope of the invention, it is proposed to combine the batteries or like sources of current for the code C. T. C. system and the mechanical selector system in such a way that the desired changes in line circuit energization required for satisfactory operation of the electro-mechanical selectors are produced without creating a difference of potential between the line wires of the proper polarity and intensity to operate the biased polar line relays of the C. T. C. system and permit any field start to shunt the line circuit during a selector code. Specifically, it is proposed, when sending selector codes, to connect the C. T. C. line battery in series with the line battery of the selector system with the polarity sense that will permit reversing the selector battery, in order to produce the alternating current components required to operate the selectors, without permitting the voltage between the line wires to reach the operating value of the biased polar line relays of the C. T. C. system.

Other objects, characteristic features, and attributes of the invention will be in part apparent, and in part pointed out, as the description progresses.

35 The accompanying drawings illustrate in a simplified and diagrammatic manner one specific embodiment of the invention applied to a shunt type C. T. C. code communication system, such as disclosed in the afore-mentioned Hailes et al.

40 Patent 2,399,734. These drawings illustrate certain relays and contacts of the complete system disclosed in this Hailes et al. application, insofar as appears to be necessary for an explanation and understanding of the present invention; and for convenience these relays and contacts are given the same reference characters as in the Hailes et al. application.

In the accompanying drawings:

45 Figs. 1A and 1B show the equipment at the control office and at one typical field location respectively;

Fig. 2 is a diagram of a simplified equivalent circuit to illustrate the way in which the batteries are combined during transmission of a selector code; and

Fig. 3 is an explanatory chart or diagram illustrating the character of energization of the line wires for a typical selector code.

Considering first the C. T. C. code communication system, it is not necessary to describe the structure and operation for the complete system, but merely point out the features or operating characters of the system material to an understanding of the present invention. This refers more particularly to the conditions under which the field stations act to shunt the line wires for an automatic field start.

Under the normal or at-rest condition shown, the line wires L₁ and L₂ are steadily energized with one polarity, conveniently termed a normal polarity, from the control office battery CB, or equivalent source of current, by a circuit which may be traced from the line wire L₁, through back contact 5 of a shift or transfer relay SH, through coils 27, 26 of the filter, back contact 25 of relay CF, front contact 24 of relay OR, back contact 23 of relay C, ballast lamp BAL to one terminal of the battery CB, assumed to be (+), through primary 29 of the impulse transformer 30, back contacts 31 and 32 of relays C and CF, coils 33, 34 of the filter, and back contact 6 of relay SH to the other line wire L₂.

Referring to Fig. 1B, this energization of the line circuit with the normal polarity causes current to flow through the line relay 2F at the typical field station illustrated, and similar line relays at all the other field stations, over a circuit path which may be traced from the line wire L₁ through coils 35, 36 of a filter, back contact 37 of relay 2LO, upper winding of relay 2F, resistance 38, lower winding of relay 2F, back contact 40 of relay 2LO and coils 41, 42 of the filter to the other line wire L₂. This normal polarity energizes line relay 2F to cause its polar contact 214 to assume the right-hand position shown in opposition to its spring bias and close a pick-up circuit for a change repeater relay 2CHP which may be traced from (+), through polar contact 214 of line relay 2F, front contact 332 of relay 2FR, back contact 333 of relay 2LOT, back contact 334 of relay 2CD, front contact 335 of relay 2FR, relay 2CHP, and through back contact 336 of change relay 2CH to (-). The change relay 2CH is normally maintained energized by a stick circuit including contacts operated to momentarily break such stick circuit upon operation of a track relay, signal, switch position indicating relay, or like device having its position indicated in the control office. The contacts 45 and 46 shown as operated by track relays ATR and TR are typical of such contacts included in the stick circuit for the relay 2CH readily traced from (+), through said contacts 45, 46, front contact 47 of relay 2CH, winding of this relay, to (-).

Thus, under the normal or at-rest condition shown, if the track relay TR, for example, should pick up or drop due to a change in the occupancy of its associated track section, the stick circuit for the change relay 2CH is momentarily broken to release this relay and close its back contact 336, thereby permitting energization of the change repeater relay 2CHP by the pick-up circuit above pointed out. The energization of the relay 2CHP and closure of its front contact 342 closes a pick-up circuit to restore the change relay 2CH and render it effective to respond to any subsequent changes in the condition of the devices to be indicated, for the purpose and in the manner more fully explained in the Hailes et al.

application above mentioned. The energization of the relay 2CHP and closure of its front contacts 337 and 427 provides stick circuits for maintaining this relay energized until the field station in question has operated to transmit its indications, one of these stick circuits being readily traced from (+), through said front contact 427, back contact 426 of a step relay V5 in multiple with a back contact of relay 2LO, front contact 335 of relay 2FR, winding of relay 2CHP, and its front contact 337 to (-). Another stick circuit includes back contacts of relay 2LO and a front contact of relay 2LOT.

Also, the energization of the change repeater relay 2CHP in the manner just described and closure of its front contact 340 provides a circuit for energizing the relay 2EO to close its front contact 354, this circuit being traced from (+), through front contact 338 of relay 2FR, back contact 339 of timing relay 2LET, front contact 340 of relay 2CHP, back contact 236 of relay 2EE, winding of relay 2EO to (-). The energization of relay 2EO and closure of its front contact 352 completes an energizing circuit for the relay 2LO including various other contacts indicated by crosses and readily traced on the drawing.

This energization of the relays 2EO and 2LO at a field station directly connects the line wire L₁ to line wire L₂ through the filter by a circuit connection through front contact 40 of relay 2LO, front contact 354 of relay 2EO, and back contact 355 of relay 2EE.

If the line relay at a field station, such as relay 2F in Fig. 1B, is deenergized, or is energized with a reverse polarity, its contact 214 is in the left-hand dotted line position, and the pick-up circuit for the change repeater relay 2CHP is open; and regardless of any deenergization of the change relay 2CH, the field station cannot operate to shunt the line circuit for a field start, so long as such condition of the line relay 2F exists. Similarly, if there are stored field starts, i. e., a CHP relay is picked up at any field locations, so long as the C. T. C. line relays such as relay 2F are deenergized, or energized with a reverse polarity, no C. T. C. field location can pick up its EO and LO relays to shunt the line circuit.

In short, in the type of code C. T. C. system under consideration, an automatic field start from one or more field stations to apply a shunt to the line circuit cannot occur unless the line relays at these field stations are energized with the normal or at-rest polarity; and this invention is concerned more particularly with the problem of preventing energization of the line relays of the field stations with such normal at-rest polarity during the transmission of a selector code involving impulses of alternate polarity.

Considering now the selector system, a shift or transfer relay SH, which is arranged to be energized upon manual actuation by the operator of a suitable key or switch S, subject to such interlock as desired and indicated generally by the back contact 9 of relay C, acts to disconnect the control office line unit and stepper from the line wires L₁ and L₂, and to connect these line wires through the front contacts 5 and 6 of the relay SH to the apparatus case of the selector system. In short, manual energization of the relay SH shifts the line wire connections from the C. T. C. system to the selector system.

It is assumed that the selector system is the well-known Western Electric train dispatching telephone system employing selector and calling key structures such as disclosed, for example, in

the patent to J. C. Field, No. 1,343,256, June 15, 1920. The control office equipment for this selector system comprises a pulsing relay PL operating spring biased contact fingers 10, 11 for pole-changing the connections between a selector battery SB, or equivalent source of uni-directional current, with respect to the input terminals of a typical filter 12. A connector relay CR operates biased contact fingers 14, 15 to connect the output of this filter 12 to the wires 17, 18 which are connected to the line wires L1 and L2 through the front contacts 5 and 6 of the relay SH when that relay is energized.

The connector relay CR is energized at the beginning of each selector code and is maintained energized throughout transmission of such code, while the pulsing relay PL is intermittently energized at time spaced intervals in accordance with the particular selected code being sent by the operation of an individual calling key or equivalent selector key structure. The code wheel CW for one such individual calling key is shown diagrammatically in the drawing as typical of such control devices; and after the calling key has been wound up and released in the regular way, the code wheel CW is turned in the counter-clockwise direction indicated by the arrow by a return spring at a regulated rate to apply to the line circuit a fixed total number of pulses, e. g. 17, divided into three groups of varying number, such as 3-10-4, 4-9-4, etc.

The selector for this system under consideration, shown diagrammatically in Fig. 1B, has an operating winding 19 connected across the line wires L1 and L2 in series with a condenser 20 of suitable capacity. This operating winding 19, when energized with current pulses of opposite polarity, operates a polarized armature 21 back and forth from and through a middle biased position. Each movement of this armature 21 from its middle position, or a movement quickly from one extreme position to the other, operates a pawl and ratchet structure to advance a stepping wheel and contact arm one step; but when the armature pauses in the middle position, as distinguished from a quick movement through that position, the stepping wheel is returned by a spring to its initial position unless a pin is provided to hold said wheel in that position. The location of these pins determines the code call for the selector. Various other operating characteristics of this type of selector are shown and described in detail in the J. C. Field patent above mentioned.

Considering a typical operation, assume that the operator desires to send a selector code and operates the switch to energize the shift relay SH at a time when the C. T. C. system is not in operation, and it is otherwise proper to pick up this relay SH and transfer from the C. T. C. system to the selector system. This deenergizes the line wires L1, L2 and all line relays such as 2F at all of the field stations, thereby rendering all of these stations ineffective to shunt the line for a field start. The operator then actuates the individual calling key for the particular selector station desired, or performs a similar function by manipulation of other selector key structures.

Assuming the code wheel CW shown is thus operated, the initial movement of this code wheel closes a circuit to energize the connector relay CR, which may be traced from (+), contact finger 50, code wheel CW, slip ring connection 51, and wire 52 through relay CR to (-).

This energization of the connector relay CR acts to connect the C. T. C. battery CB and the selector battery SB in series to the line wires L1 and L2 with the reverse polarity by a circuit connection which may be traced from line wire L1, front contact 5 of relay SH, wire 17, contact 14 of relay CR, telephone filter 12, wire 55, battery CB, upper or (+) terminal of battery CB, wire 56, contact 10 of relay PL, through battery SB, contact 11 of relay PL, filter 12, contact 15 of relay CR, wire 18, and front contact 6 of relay SH to the other line wire L2.

It will be noted that the batteries CB and SB are connected to act accumulatively, as indicated in Fig. 2, so that the potential across the line wires L1 and L2 is the sum of the voltages of these two batteries. Generally speaking, the impedances and number of the connections for C. T. C. field stations and selectors are much alike, so that ordinarily the voltages of the two batteries CB and SB for operating the C. T. C. field stations and the selectors respectively are much the same; and for purposes of explanation, it is assumed that these batteries are the same and each is a 100 volts.

It should also be noted that when the connector relay CR for the selector system is energized to provide the first energization of the line circuit, the polarity of this energization is opposite to the normal at-rest polarity, so that contact fingers of all of the line relays, such as the contact finger 214 of line relay 2F, remain in the reverse or dotted line position, which they assumed when relay SH picked up and deenergized line wires L1 and L2, thereby maintaining open the circuit for providing a field start. Considering this reversal of polarity more in detail, upon referring to Fig. 1A, it will be noted that the line wire L1 is connected to the (+) terminal of the battery CB under the conditions shown with the relay SH deenergized; but if this relay SH is energized, then the same line wire L1 is connected through front contact 5 of relay SH, wire 17, contact 14 of relay CR, filter 12, and wire 55 to the (-) terminal of the battery CB.

The initial energization of the line circuit at the beginning of a selector code as just described, sends current through the operating winding 19 of all of the selectors during the charging time of the associated condenser 20, so that the armature of each selector is moved to one extreme position and then, after the condenser 20 becomes fully charged, assumes its middle position. This serves to restore to the initial position the stepping wheel for any selector that may happen to be in an intermediate position.

Referring to the explanatory diagram in Fig. 3, this clear-out pulse, which is caused by the energization of the line circuit by the two batteries CB and SB acting cumulatively represents a line circuit energization of (-) 200 volts on the assumption previously mentioned that each of these batteries is 100 volts.

After this preliminary movement of the code wheel CW, the first tooth of this wheel lifts the arm 59 into engagement with a stationary contact 58 to close a circuit readily traced on the drawing for energization of the pulsing relay PL, thereby operating its contacts 10, 11 to pole-change the connections and in effect connect the batteries CB and SB in opposition. Assuming these batteries to be equal, the impressed potential across the line wires L1 and L2 drops to zero, as indicated in Fig. 3, for the first counting pulse designated 1. When the first tooth passes from

under the contact arm 50 and the relay PL is deenergized, the line wires L1, L2 are again energized for count 2 with a potential of (-) 200; and the next time the contact arm 50 is raised by the code wheel CW for count 3 of the selector code, the potential across the line wires L1 and L2 again falls to zero.

In the case of the code 3-10-4 assumed, the line circuit condition after the third counting pulse is maintained until the condenser 20 assumes a stable condition and no more current flows through the operating winding 19 of the selector, whereupon its armature assumes the middle position. In accordance with the well-known plan of operation for this type of selector system, the stepping wheels of those selectors having a code call beginning with a count of 3 are held by a pin while their armatures are in the middle position, but all of the other selectors having a different code are restored to the initial position. This same operation is repeated for two more groups of pulses to make up a predetermined code count of 17 in the particular arrangement assumed; and that at the end of the transmission of these 17 pulses in three groups of a certain number in each group, such as 3-10-4, there is only one selector having this particular code call which has had its stepping wheel advanced the full number of steps to its final position; and hence the last pulse is effective at this one selector to close a circuit for ringing the bell or perform any other desired function. After the last or bell ringing impulse, the code wheel is shaped to cause energization of the connector relay CR for a time while the pulsing relay PL is deenergized. This restores the selector in question to its initial condition; and when the code wheel assumes its initial position shown, the relay CR is released.

From the standpoint of the operation of the selector, which is connected across the line wires L1 and L2 through a condenser 20 of the proper capacity, these changes in line circuit energization between zero and (-) 200 indicated in Fig. 3, are in effect alternating components. It may be said that each time the line circuit is energized, the condenser 20 is charged and the operating magnet 19 of the selector is energized with current of one polarity, and each time the line circuit is deenergized, the discharge of the condenser 20 causes a flow of current through the operating winding of the selector in the opposite direction. The net result is that the selector operates the same as if 100 volt impulses of alternate polarity were impressed across the line wires L1 and L2.

Stated another way, in accordance with the well-known transposition theorem, the inclusion of the C. T. C. battery CB in the circuit for energizing the line wires L1 and L2 for selector code transmission does not alter the current conditions produced by the selector battery SB alone, except with respect to the impedance that the C. T. C. battery CB may add to the circuit.

Referring particularly to a diagram of Fig. 3, it can be seen that during the transmission of this typical selector code, the voltage of the line wire L1 with respect to L2 varies from (-) 200 to zero, but the line wire L1 never becomes positive with respect to the line wire L2. Consequently, current through the line relays of the C. T. C. field stations, such as the relay 2F in Fig. 1B varies from a reverse polarity to zero. The armature of the line relay 2F is biased by a spring, as indicated conventionally, to assume the same left-hand position when deenergized as it assumes when en-

ergized with the reverse polarity. In short, during selector code transmission the armature of the line relay 2F remains in the left-hand position, being held there by the biasing spring alone, or by the biasing spring plus electro-magnetic attraction.

In this way, the line relays of the C. T. C. field stations are prevented from assuming a condition, even momentarily, for a field start; and hence no stored start or change in track circuit occupancy or the like tending to create a field start can become effective while the system is set for transmission of selector codes, thereby obviating any mutilation of the selector codes by a shunting of the line circuit for a field start during the transmission of such selector codes.

In this connection, it should be appreciated that it is not necessary that the C. T. C. battery CB and selector battery SB should exactly equal each other and provide a zero potential for the line circuit. This condition has been assumed to simplify an explanation and understanding of the nature of the invention, but it can be seen that any relationship of battery voltages may be employed, so long as there is not enough difference of potential between the line wires of the normal at-rest polarity to provide pick-up energy for the C. T. C. line relays. Such pick-up energy is ordinarily in the order of 50 volts, and the voltage for the selector battery SB may exceed that of the C. T. C. battery CB and cause a positive energization of the line wire L1 with respect to L2, provided such positive energization is not sufficient to operate the contacts of the C. T. C. line relays 2F against their spring bias.

It should perhaps be pointed out that a C. T. C. battery CB, separate from the selector battery SB, is ordinarily available and can be readily used in conjunction with the transmission of selector codes as well as for C. T. C. codes, without material change in the over-all power cost. It is ordinarily expedient to employ the full voltage of the C. T. C. battery CB, but if desired, the wires 55, 56 may be connected so as to use the appropriate portion of this battery; or to include extra cells if the selector battery should happen to be substantially greater than the C. T. C. battery.

The particular construction and arrangement of parts shown and described merely represents one typical specific embodiment of the invention; and I desire to have it understood that various modifications, adaptations and additions may be made in this particular construction and arrangement of parts without departing from the invention.

What I claim is:

1. In a system of centralized traffic control combined on the same line wires with a selector system, a plurality of selectors bridged across said line wires with coupling condensers, a plurality of field station equipments each including a polar line relay connected across said line wires and operable only when said line relay is energized with a particular polarity to permit that field station equipment to shunt the line wires for creating an automatic field start, calling means in a control office including a pole-changed selector battery for changing the energization of said line wires to operate said selectors, and manually operable means for rendering said calling means effective and for also connecting another source of current to the line circuit in series with said selector battery, said another source of current and said pole-change selector battery acting

cumulatively and in opposition alternately to provide pulses on said line wires of a polarity opposite said one particular polarity and at an energy level suitable for operating said selectors.

2. In a system of the character described for combining a centralized traffic control code system and a selector code system on the same line wires, code transmitting means at a plurality of field stations each including a polar line relay and operable only if said line relay is effectively energized with a particular polarity to shunt said line wires for an automatic field start, code transmitting means in the control office including a source of direct current for normally energizing said line wires with said particular polarity and operable in response to said automatic field start to energize said line wires with the other polarity, mechanical selectors connecting across said line wires with coupling condensers, a selector battery in a control office, calling means in said control office for intermittently pole-changing the connections between said selector battery and said line wires in accordance with a selector code, and manually operable means for rendering said calling means effective and for also connecting said source of direct current in series with said selector battery to provide intermittent energization of said line wires with a polarity different from said particular polarity during the pole-changing of the selector battery for transmission of a selector code.

3. A combined centralized traffic control and mechanical selector system comprising, a pair of line wires connecting a control office and a plurality of field locations, code transmitting means at certain of said field locations each including a polar line relay normally energized with one polarity, mechanical selectors at the other field locations connected across said line wires by coupling condensers, calling means in the control office including a selector battery and a pulsing relay for pole-changing the connection between said selector battery and said line wires in accordance with a desired selector code, code transmitting and receiving means at the control office including a separate battery normally energizing said line wires with said one polarity, and manually controllable means for rendering said calling means effective and for connecting said separate battery across the line wires with its polarity reversed in series with said selector battery and independently of said code transmitting and receiving means, whereby a potential between said line wires is maintained independently of the pole-changing of the selector battery to prevent effective energization of said line relays with said one polarity during transmission of a selector code.

4. In a centralized traffic control and selector system combined on the same pair of line wires, a plurality of field station equipments each including a polar line relay connected across said line wires, each of said field station equipments being operable only if its polar line relay is energized with a particular polarity to create a field start condition by shunting said line wires, code transmitting and receiving means in a control office including a coding source of current for transmitting control codes to selected field station equipments and for initiating transmission of indication codes from a selected field station equipment in response to a field start condition, selectors connected across said line wires at field locations, calling means in the control office including a selector battery and a pulsing relay for

pole-changing the connections between said battery and the line wires in accordance with a selector code, and manually controllable means in the control office for rendering said calling means effective and said code transmitting and receiving means ineffective and for also connecting said coding source of current with its polarity reversed with respect to the line wires in series with said selector battery, whereby during the transmission of a selector code the line wires do not assume such difference of potential required for the effective energization of said line relays with said particular polarity to permit a field start.

5. In a code communication system for railroads, a pair of line wires connecting a control office and a plurality of field stations, code transmitting means at each field station including a polar line relay and operable only when said line relay is energized with a particular polarity to govern the energization of said line wires for transmission of a field start condition to the control office, a mechanical selector bridged across said line wires with a coupling condenser and responsive to the number of changes in the energization of said line wires during a selector code, said selector requiring for its operation changes in the level of energization of said line wires equivalent to pulses of a certain voltage and alternate polarities, coding equipment at the central office normally energizing said line wires with a predetermined voltage of said particular polarity to maintain said line relays energized to permit an automatic field start, and manually operable means in the control office including a selector calling key for intermittently energizing said line wires with pulses of the same polarity opposite to said particular polarity in accordance with a selector code, said intermittent energization of said line wires being at a voltage higher than said predetermined voltage and substantially double said certain voltage required for selector operation by alternate polarities, said higher voltage acting by charging and discharging said coupling condenser at a high energy level to cause operation of said selector substantially the same as in response to pulses of said certain voltage and of alternate polarity.

6. In a code communication system of the character described for railroads, a pair of line wires connecting a control office and a number of field stations, a plurality of mechanical selectors bridged across said line wires with coupling condensers and responsive to the energization of said line wires, coding equipment at each field station connected to said line wires and including a polar relay governing the operation of said equipment, said coding equipment including means effective only if said line relay is energized with one particular polarity to apply a shunt to said line wires for a field start, transmitting means at the control office including a source of direct current for energizing said line wires with said one particular polarity for the normal at-rest condition of the system, an additional source of direct current in the control office, and manually operable means in the control office including selector calling keys for intermittently energizing said line wires from both of said sources of current acting cumulatively and in opposition alternately to form pulses effective for operating said mechanical selectors and all having the same polarity opposite to said one particular polarity, whereby the condenser coupling the mechanical selector to the line wires is charged and discharged at an energy level by the combined sources of current to cause

operation of the selector substantially the same as in response to pulses of alternate polarity from said additional source alone.

7. In a communication system of the character described, a pair of line wires connecting a control office and a plurality of field stations, code transmitting means at each field station including a polar line relay governing in one energized position only the automatic field start control from that field station, a plurality of mechanical selectors bridged across said line wires with coupling condensers and operated by changes in line wire energization, coding means in the control office including a selector source of current and code generating devices for pole-changing the electrical connections between said selector source of current and said line wires in accordance with the desired selector code for selective operation of said selectors, and means for rendering said coding means effective and for connecting another source of current to said line wires in series with

said selector source of current to prevent energization of said line wires with a polarity to energize said line relays to said one energized position, the level of energization of said line wires by combining said sources of current being changed by pole-changing said selector battery to cause operation of said selector.
